UNITED STATES PATENT OFFICE.

WILLIAM H. PRATT, OF MOUNT VERNON, OHIO.

TELEGRAPH-POLE.

SPECIFICATION forming part of Letters Patent No. 488,830, dated December 27, 1892.

Application filed March 25, 1892. Serial No. 426,456. (No model.)

To all whom it may concern:

Be it known that I, WILLIAM H. PRATT, a citizen of the United States, residing at Mount Vernon, in the county of Knox, State of Ohio, 5 have invented certain new and useful Improvements in Telegraph-Poles, of which the following is a specification, reference being had therein to the accompanying drawings.

This invention relates to certain new and 10 useful improvements in supports or poles for telegraph, electric light and other wires, or other purposes for which such structures may be employed.

It has for its objects among others to provide 15 a cheap and simple light yet strong pole with anchorages which are adapted for all the conditions under which it may be found desirable to secure the pole. I provide an anchorage templet which serves to hold the anchor rods in proper position and to bind the 20 upper ends thereof together in fixed relation; this templet is provided with pivoted clips to further hold the parts firmly together. The rods of the pole are suitably braced and are held 25 at the proper distance apart at suitable intervals by bands. By my construction the pole can be easily and quickly erected, and the same may be adjusted and plumbed by means of nuts on the lower ends of the pole- 30 rods which are independently adjustable.

Other objects and advantages of the invention will hereinafter appear and the novel features thereof will be specifically defined by the appended claims.

35 The invention is clearly illustrated in the accompanying drawings, which, with the letters of reference marked thereon, form a part of this specification, and in which

Figure 1 is a side elevation of my improved 40 pole and anchorage, broken away. Fig. 2 is a detail in side elevation showing a slightly modified form of pole. Fig. 3 is a plan view of the top plate. Fig. 4 is a like view of the anchorage-templet. Fig. 5 shows in side elevation and plan respectively the wall anchor. 45 Fig. 6 shows in side elevation a rock anchor.

Like letters of reference indicate like parts throughout the several views in which they appear.

50 Referring now to the details of the drawings by letter, A designates twisted bars having preferably pointed ends as seen in Fig. 1

and their upper ends bent at right angles to the length of the bars to form the horizontal flanges *a* which are each perforated for the 55 reception of the lower ends of the pole-rods. These bars are to be driven into the ground and may be of any desired length, depending somewhat upon the height and weight of the pole which they are to hold. While I have 60 chosen to show my anchorage bars and the pole itself in triangular form it will of course be understood that this invention is not restricted to such form although it is the preferable one; other forms may be employed without departing from the essence of the invention. 65 When this triangular design is employed I employ an anchorage-templet *B* which has at each of its inner angles a rectangular recess *b* for the anchor bars and across each 70 angle there is arranged a clip or short arm *B'* which is pivotally held to the templet at one end as seen at *b'* and its other end designed to be held by any suitable removable means as for instance a bolt and nut. The anchor 75 bars *A* are driven through this templet the bars fitting in the recess at the angles and when the anchorage is in place the clip is swung back to allow the templet to be drawn upward over the top of the anchorage; the 80 clips are fastened beneath the flanges *a* of the anchor bars as will be readily understood.

When a guy anchor is necessary or desirable I may employ a guy anchor similar to one of the anchor bars which is driven into the 85 ground at any convenient point and to this may be secured the guy from the top of the pole.

It is sometimes desirable to erect a pole on ground where it is impossible to drive anchor 90 bars, say upon a rock and for such occasions I provide rock anchors, one of which is seen in Fig. 6, and consists of a rod or bar *C* designed to be cemented or otherwise held in holes drilled in solid rock and at the upper 95 end provided with a horizontal flange *c* perforated for the reception of the lower end of a pole-rod the same as the form seen in Fig. 1. Of course as many of these rock anchors will be used as there are rods in the pole. 100

In Fig. 5 I have shown a wall anchor to be secured to faces of masonry or other vertical faces; it consists of a right-angled plate *D* having upon its horizontal portion holes *d* for

the reception of the lower ends of the pole-
rods and braced by a suitable inclined brace
arm D'. The vertical portion of this plate is
provided with suitable holes d' for the recep-
tion of the means which hold it to the wall.

- 5 The pole consists of a plurality of vertical
rods of any desired size and length, shown in
triangular form as that is the form preferred,
and the lower ends are screw threaded and
10 passed through the holes in the flanges of the
anchors, no matter which form of anchor is
employed, and are provided with adjusting
nuts e on the ends of the said rods E and jam
nuts e' on the said rods above the said flanges
15 as seen in Figs. 1 and 2. The upper ends of
the rods are also screw threaded as seen in
Fig. 1 and F is a top plate provided with holes
f through which the upper ends of the rods
pass and above this plate are the nuts F' on
20 the ends of the rods. The top plate is further
provided with a central opening f' for the re-
ception of the shank of an insulator G as seen
in Fig. 1.

H is a metallic angle cross arm secured to
25 the pole in any suitable manner and the hori-
zontal portion thereof is provided with ver-
tical openings for the reception of the shanks
of the insulators G'.

The pole is braced interiorly by the inclined
30 and crossed bars I which, as shown in Fig. 2,
are continuous from the top to the bottom of
the pole, and are held at their bends by me-
tallic bands or rings I' shrunk or welded on
in any suitable manner.

35 In the form shown in Fig. 1 the lacing or
brace bars I are in sections with their ends
upset and formed with openings for the pas-
sage of the pole-rods, and J are horizontal tie
bands which also have apertured portions
40 through which the pole-rods pass. The aper-
tured portions of the bands J are held between
the apertured ends of the bars I as seen in
Fig. 1, and by tightening the nuts at the up-

per ends of the rods the parts are all brought
together and securely held in their proper 45
positions.

K are tie bands holding the lower ends of
the pole-rods as seen in Figs. 1 and 2.

Modifications in detail may be resorted to
without departing from the spirit of the in- 50
vention or sacrificing any of its advantages.

What I claim as new is:—

1. The combination with a pole formed of
rods, of an anchor having horizontal flanges
for the passage of the rods, and an anchor- 55
templet, having movable retaining devices as
set forth.

2. The combination with a pole, of an an-
chor adapted to support the pole, and an an-
chor-templet provided with pivoted clips, as 60
set forth.

3. The combination with a pole, of an an-
chor formed of bars with horizontal flanges,
and an anchor-templet provided with recesses
at its inner angles, and pivoted clips, sub- 65
stantially as specified.

4. The combination with an anchor having
horizontal flanges with apertures, of a pole
formed of rods having their lower ends passed
through said apertures, and nuts upon the 70
said rods above and below the flanges, sub-
stantially as specified.

5. A pole formed of rods, sectional inclined
brace bars with their ends sleeved on the rods,
and tie bands arranged at substantially right 75
angles to the rods and having their outer por-
tions sleeved on the rods between the ends of
the brace bars, substantially as shown and
described.

In testimony whereof I affix my signature 80
in presence of two witnesses.

WILLIAM H. PRATT.
